DRYING APPARATUS

Hermann Haas, Lenne, Germany

Application February 27, 1931, Serial No. 518,619
In Germany March 11, 1930

2 Claims. (Cl. 34—19)

This invention relates to a continuous drying apparatus of that type which comprises a drying chamber divided into a plurality of communicating sections through which the material to be dried passes progressively, and which is also provided with means for establishing a local circulation of the drying medium through each section as well as a progressive movement of the drying medium through the chamber from one end to the other.

In prior drying apparatus of this type it has been customary to provide means for heating locally the drying medium which is circulated through each section of the drier.

The present invention has for its object to provide a drying apparatus of this general type in which the drying medium which is being locally circulated in the separate sections is heated from a central or common heating apparatus that may be located at a greater or less distance from the drying chamber. The drying medium which is thus heated at the central heating station is distributed to the different sections of the drier in the proportions needed to maintain the desired temperature and drying conditions in each section.

In the accompanying drawing wherein I have illustrated a selected embodiment of my invention, Fig. 1 is a side view of a drier embodying my invention;

Fig. 2 is a sectional view on substantially the line 2—2, Fig. 1;

Fig. 3 is a section on the line 3—3, Fig. 2.

In the drawing 1 indicates the drying chamber which is herein shown as divided to form a plurality of sections A, B, C, D, E, etc. which are connected to each other. The material to be dried is passed progressively through the connecting sections, said material entering the section A at the left hand end and progressing through the various sections and being discharged from the right hand end of section E.

Associated with each section of the drier and situated at one side thereof is a circulating passage H which is separated from the drying chamber by a partition 2.

Each circulating passage H communicates with the drying chamber through two openings 3 and 4 that are formed in the partition 2, the opening 3 being at the upper part of the partition and the opening 4 at the lower part thereof.

5 indicates a fan or air-forcing device which operates to create a local circulation, indicated by the arrows 6, Fig. 3, through each section

of the drier and the corresponding circulating passage H.

In accordance with the present invention the heated air which is utilized for drying the material in the drying chamber 1 is furnished from an air heater L that is common to all of the sections A, B, C, D, etc. of the drying chamber. This air heater L may have any suitable or usual construction. It is shown as having associated therewith a fan or blower V by which air is supplied to the heater for being heated and said heater is also provided with a discharge pipe R provided with branches 8, one branch leading to the lower portion of each of the circulating passages H. Each branch 8 is provided with a valve by which the amount of heated air delivered through the branch may be regulated, these valves being indicated at S¹, S², S³, S⁴.

G indicates an aspirator or suction device which is connected to the entering end of the drying chamber 1. At the other end the drying chamber 1 is provided with an inlet opening O which leads into the last section E. The operation of the suction device G is to cause a gradual movement of the air through the drier from the delivery end to the entering end. If desired, the air which is fed to the heater L by the blower V may be taken from the section E through the medium of a pipe connection K.

In the operation of the device the blowers 5 will create a local circulation of air in each section of the drying chamber and through the operation of the heater L and blower V hot air will be supplied through the branch pipes 8 to the various sections of the drier, such hot air commingling with and forming part of the local circulation in each section indicated by the arrows 6.

By regulating the valves S¹, S², S³, S⁴, etc. the amount of hot air which is delivered to each section can be adjusted so as to maintain in each section A, B, C, D the desired drying conditions. The suction device G will maintain a progressive circulation of air from the section E through the various sections to and through the section A.

By providing a single air-heating device for all of the various sections of the drier it is possible to locate this heating device at a greater or less distance from the drying chamber and also to use heat which would otherwise go to waste for heating the air.

I claim:

1. A drying apparatus comprising a drying chamber through which the material to be dried passes from one end to the other and which is divided into a plurality of communicating sections, a circulating passage for each section, each circulating passage communicating with the drying space of its section at both the top and the bottom thereof, a fan in each circulating passage at the lower end thereof for producing a local circulation through said passage and the corresponding section of the drying chamber, means for producing a progressive circulation from the discharge end of the drying chamber to the entering end, an air heater common to all of the sections but separate from and located exterior to the drying chamber, a conduit leading from said air heater and provided with a branch leading into each circulating passage at the bottom thereof, a valve in each branch, and means independent of the fans for delivering heated air from the air heater into said circulating passages through the branches of said conduit.
2. A drying apparatus comprising a housing enclosing a drying chamber through which the material to be dried passes from one end to the other and which is divided into a plurality of communicating sections, vertical partitions forming

within said housing circulating passages, one for each section, each circulating passage having a dimension lengthwise of said housing equal to the corresponding dimension of the corresponding section and extending from the top to the bottom of the housing, and communicating with the drying space of its section at both said top and bottom thereof, a fan in each circulating passage at the bottom thereof for producing a local circulation through said passage and the corresponding section of the drying chamber, means for producing a progressive circulation from the discharge end of the drying chamber to the entering end, an air heater common to all of the sections of the drying chamber but separate from and located exterior thereto, a conduit leading from said air heater and provided with branches, one leading into each circulating passage at the bottom thereof adjacent one end, and means independent of the fans for withdrawing air from the delivery end of the drying chamber and passing it through the air heater and into said conduit and through said branches into the circulating passages and a valve in each branch to control the flow of heated air therethrough.
